UNITED STATES PATENT OFFICE.

RUDOLPH POKOY, OF MARBURY, ALABAMA.

INCUBATOR.

1,286,765.

Specification of Letters Patent.

Patented Dec. 3, 1918.

Application filed November 7, 1916. Serial No. 129,966.

To all whom it may concern:

Be it known that I, RUDOLPH POKOY, a subject of the Emperor of Austria-Hungary, residing at Marbury, in the county of Autauga and State of Alabama, have invented certain new and useful Improvements in Incubators; and I do hereby declare the following to be a full, clear, and exact description of the invention, such as will enable others skilled in the art to which it appertains to make and use the same.

This invention relates to incubators, and an object of the invention is to incorporate therein certain constructions that will increase the efficiency of the incubator, and will admit of the proper temperature being maintained when the incubator is in operation.

Another object of the invention is the provision of an incubator wherein the different parts constituting the incubator will be so arranged that they can be conveniently removed and replaced by new parts when desired.

Other objects will appear and be better understood from that embodiment of my invention of which the following is a specification, reference being had to the accompanying drawings forming a part thereof, in which:

Figure 1 is a vertical front elevation of the incubator with the front and upper walls swung to open position.

Fig. 2 is a vertical sectional view, taken on the line 2—2 of Fig. 1.

Fig. 3 is a vertical front sectional view of the incubator, showing the interior thereof.

Fig. 4 is a vertical sectional view, taken through the filling spout of one of the heating tanks.

Fig. 5 is a detail view through the auxiliary air inlet.

Fig. 6 is a detail sectional view, taken through the regulating means for the damper operating mechanism.

Fig. 7 is a detail view, showing the air inlet controlling damper for the lower heating compartment.

Fig. 8 is a top plan view of the regulating means for the damper operating mechanism.

Fig. 9 is a vertical elevation of a thermometer and the support therefor for determining the degree of temperature within the intermediate or egg compartment, the said

thermometer or support being shown removed from the incubator, and

Fig. 10 is a detail perspective view of the forward end of the movable element which operates the dampers.

Referring to the drawings in detail, the incubator is shown as consisting of a casing having formed therein an upper compartment 2, an intermediate compartment 3, and a lower compartment 4. The walls of the incubator are formed in the usual or any appropriate manner. The front of the incubator is closed by an inner and outer wall, the inner wall having formed therein an upper door 5, which opens into the upper end of the intermediate compartment 3, an intermediate door 6, which also opens into the intermediate compartment 3, and a lower door 7 which closes the forward side of the lower compartment 4. These doors 5, 6, and 7 are hinged, respectively, to strips 8 and 9. The outer wall consists of a door 10, which has hinge connection to one of the side walls of the casing, and the door 6 in the inner wall is provided with an opening 11, which receives a suitable lens, the said opening 11 being adapted to register with a similar opening 12 formed in the door 10, when the latter is in closed position, and within which is mounted another lens. The openings 11 and 12, and the lenses mounted therein, serve to provide a window by which the interior of the intermediate compartment 3 can be inspected.

The upper wall 10' is hingedly secured in position and forms means whereby access may be readily had to the upper portion of the incubator. The opposite side walls of the intermediate compartment are provided with opposed ledges 13 which form

rests for an egg tray, designated 14, in Fig. 2 of the drawings. The upper wall of the intermediate compartment 3 is provided with a pair of spaced openings 15, and the lower wall of the intermediate compartment is also provided with a pair of spaced openings 16. The upper compartment 2 and the lower compartment 4 constitute the heating compartments of the incubator and by virtue of the openings 15 and 16 formed in the upper and lower walls of the intermediate compartments the heat can pass from the upper and lower compartments 2 and 4 into the intermediate or egg compartment 3.

Each of the compartments 2 and 4 has

mounted therein a heater 17. These heaters 17 are identical in construction, and a description of one is deemed sufficient for both. Each heater consists of a rectangular shaped tank, having mounted therein a partition wall 18, which divides the tank into upper and lower compartments. The lower compartment, designated 19, is adapted to receive hot water, and the upper compartment 10 receives a heating element 20, formed, preferably, of soapstone, or other material which will readily absorb heat, and heat the water in the lower compartment 19. The compartment 18 is provided, at a medial point, with 15 an opening which receives one end of a filling spout 21. This filling spout 21, as shown in Fig. 4 of the drawings, consists of a tubular body having its upper end closed by a removable disk 22, which has a central opening therein, and mounted within the spout, and movable therein, is a disk 23, having an opening 24 therein, which is disposed in direct alinement with the opening in the disk 22. A coil spring 25 is interposed between 20 the disk 22 and the disk 23 and serves to hold the disk 23 spaced below the disk 22. An annular flanged member 26 is threadedly mounted within the filling spout 21 and engages the lower side of the disk 23, and has 25 its lower side provided with a plurality of openings 27. The disks 22 and 23, and the element provide a whistle that will be operated to give a sound when the water within the tank 17 becomes heated to the degree 30 where steam will be generated, the steam generated passing through the openings in the disks 22 and 23 and the flanged element 26, and producing a sound. A flanged cap 28 engages over the disk 22 and has threaded engagement with the upper end of the spout 21, and serves to retain the disk 22 in operative position, the upper side of the cap having an opening 29 therein for the escape of the steam. A pair of handles 31 are 35 pivotally connected to the sides of the heater, as at 30, and the handles form means for the easy removal of the heater. The lower compartment 4 has one of the end walls thereof provided with an air inlet opening 32, and 40 a manually operated damper 33 is adapted to regulate the passage of air through the opening 32 into the lower compartment 4.

A pair of rectangular shaped dampers 34 underlie the upper wall of the intermediate 45 compartment 3 and are adapted, when the heat within the intermediate compartment 3 exceeds a predetermined degree to move upwardly and close the openings 15, so as to cut off communication between the upper or 50 heating compartment 2 and the intermediate compartment 3. These dampers 34 have their forward ends connected by a bar 35, which is of angular shape in cross section, and the rear ends of the dampers 34 have 55 openings therein for the reception of the

bills of hooks 36, which are secured to the rear wall of the intermediate compartment 3. A bracket 37 is located within the intermediate compartment 3, and is of angular shape and has one leg thereof secured to the rear wall of the intermediate compartment and its opposite end underlying the space between the dampers 34. A second bracket 38 is mounted on the horizontal arm of the bracket 37, and has its opposite ends 39 projecting laterally beyond the opposite longitudinal edges of the horizontal arm of the bracket 37. One of the arms 39 of the bracket 38 supports a thermostat 40, formed of a pair of superposed wafers, and mounted on the other arm 39 of the bracket 38 is another thermostat 41 composed of a single wafer. An expansion bar 42, of arcuate shape, has its opposite ends overlying and resting on the respective thermostats 40 and 41, and when the thermostat expands, the rod 42 will be raised upwardly. The rod 42 is received between pairs of spaced studs 43, which project vertically from the bracket 38. A wedge shaped element 44 rests upon the upper side of the rod 42 and is provided with a longitudinally extending channel 45, the lower wall of which is inclined toward the restricted end of the element 44. An elongated horizontally disposed and vertically movable element 46 is disposed above the element 44 and has its opposite sides provided with upwardly extending elongated flanges 47, which are provided adjacent their rear ends with opposed openings 48 through which passes a transverse shaft 48, the opposite ends of the shaft 48 extending beyond the outer sides of the flanges 47 and journaled in the sides of the inverted U-shaped frame 49, which is secured to the under side of the upper wall of the intermediate compartment 3. A vertical pin 50 has its upper end extended through an opening in the movable element 46 at a point in advance of the shaft 48, and a pin 51 extends through an opening in the upper end of the pin 50 and is journaled in the flanges 47. The lower end of the pin 50 extends into the channel 45 formed in the element 44, and is provided with a head, which prevents the lower end of the pin 50 from being raised vertically out of the channel 45 by engaging opposed inwardly directed flanges formed on the upper walls of the channel 45, as shown more particularly in Fig. 2 of the drawings. Located within the intermediate compartment 3 and disposed in rear of the bracket 38 is a vertical rod 51^a, which has the upper end thereof bent to provide a loop which is extended through an opening 52 in the rear end of the plate 46. The rod 51^a is slidably received by an opening formed in the horizontal arm of the bracket 37. A horizontal rod, designated 52, is located at the forward end of the plate 46 and has one 57

end extended through an opening in the vertical flanged portion of the bar 35 and terminally extended therebeyond, and the opposite end of the rod 52 extends through a sleeve formed on the forward end of the plate 46 by a longitudinal depression in the plate, the terminal of the mentioned end of the rod 52 being coiled and fitted in a circular recess formed in the upper side of the plate 46, the said circular recess being disposed in concentric relation with the opening which receives the upper end of the pin 50. An operating rod 53 is slidably extended through one of the side walls of the casing and has the inner end thereof connected to the element 44, and the opposite end located exteriorly of the incubator and provided with a manipulating head 54. When the temperature in the intermediate compartment exceeds a predetermined degree, the thermostats 40 and 41 will expand and cause the rod 42 and the element 44 to be moved upwardly and effect engagement between the lower wall of the channel 45 and the lower end of the pin 50, and continued upward movement of the element 44 will rock the forward end of the element 46 upwardly, and cause the rod 52 to be moved upwardly and effect closing of the dampers 34, thereby cutting off communication between the heating compartment 2 and the intermediate compartment 3. When the rod 53 is moved inwardly the enlarged end of the element 44 will be brought nearer to the highest point on the curved surface of the rod 42 and the lower wall of the channel 45 will be brought nearer to the head of the pin 50, thereby admitting of the dampers being closed upon less degree of expansion of the thermostats 40 and 41, than it takes to operate the dampers when the restricted end of the element 44 is presented to the highest curved point on the rod 42. It will, therefore, be seen that the element 44 will serve as a regulator to effect closing of the damper at any desired temperature. The lower end of the vertical rod 51^a carries a section 51^b, which has adjustable connection with the rod 51^a by means of an adjusting nut 51^c. The section 51^b has connection with the inner end of a horizontally disposed lever 55, the said lever being pivoted to a bracket 56 mounted on the lower wall of the intermediate or tray compartment 3, at a point in rear of the openings 16. The forward end of the lever 56 has connection with a rod 57, which extends at right angles to the lever 55 and has secured to the opposite ends a pair of dampers 58, which overlie the openings 16 in the lower wall of the intermediate compartment. When the thermostats 40 and 41 are expanded to effect movement of the dampers 34 to closed position, the vertical arm 51^a will be pulled upwardly and effect the lowering of the forward end

of the lever 55 so as to move the damper 58 to closed position, so as to cut off communication between the intermediate compartment 3 and the lower compartment 4 of the incubator.

A vertically disposed air flue 59 is formed on the incubator and is located at that side opposite the one that has the air inlet opening 32 formed therein, the said flue being, as shown in Fig. 3 of the drawings, restricted at its lower end and communicates with an opening 60 formed in the adjacent wall of the lower compartment 4. The upper end of the flue 59 is closed by a wall 61, which has an opening 62 therein. A tubular shaped support 63 is secured to the wall 61 and has its upper end provided with an offset pair of spaced arms 64. A lever 65 is pivoted between the arms 64 and has one end connected to the upper end of a vertical stem 66 carried by a damper 67 which overlies the opening 60 in the wall 61. When the lever 65 is moved in one direction, the damper 67 will close the opening 60, so as to prevent entrance of air into the flue 59. A weight 68 is adjustable on the free end of the lever 65, for the purpose of regulating the amount of force for rocking the lever 65. A rod 69 is operable through the tubular support 63 and has its upper end connected to the lever 65, at a point in rear of the fulcrum thereof, and the lower end of the rod 69 extends into the flue 59 and has connection with the outer end of a horizontally disposed rod 70, which extends through an elongated slot formed in the adjacent wall of the intermediate compartment 3 and has its inner end extended through the bifurcated end of an arm 72 carried by the adjacent arm 39 of the bracket 38. The inner terminal of the rod 70 is bent downwardly, as shown at 71, and overlies that end of the bar 42 which rests upon the uppermost wafer of the thermostat 40. When the thermostats 40 and 41 raise the rod 42, the rod will engage the bent terminal 71 of the rod 70 and raise the inner end of the rod 70 upward, causing the outer end to pull the rod 69 downwardly and cause that end of the rod 55 which has connection with the stem 66 of the damper 67 to be raised upwardly, so as to raise the damper 67 above the opening 60 and admit of entrance of air into the flue 59 and thence through the opening 60 to the lower compartment 5.

In Fig. 1 of the drawings a brooder, designated as an entirety by the numeral 73, is shown associated with the incubator and located at the side opposite the one having the flue 59. The supporting brackets are located on the opposite sides of the brooder 73 for supporting the brooder and each consists of a V-shaped element 74, which has the free ends of its sides connected with the incubator by means of suitable plates 75. The apex of the V-shaped bracket 74 has connec-

tion with the bill of a hook 76, the terminal of the shank of the hook being extended around the forward side of the brooder and secured thereto by means of a set screw fastening element 77. The brooder 73 has that wall adjacent the incubator provided with an opening that registers with an opening 78 in the incubator wall so as to communicate the interior of the brooder with the intermediate or egg compartment 3 of the incubator. An air flue 78' is provided for the brooder and the entrance of air into the brooder therefrom is controlled by a suitable valve (not shown).

15 Located within the intermediate or egg compartment 3 is a thermometer 79. This thermometer 79, as shown in Fig. 1, is disposed directly opposite the windows in the front wall of the intermediate or egg compartment 3 and the said thermometer is, as shown in Fig. 9, carried by a laterally extending bracket 80, which has its outer end provided with a sleeve 81. This sleeve 81 receives the upper end of the outer slidable member of a vertically disposed telescoping support 82, the said sleeve 81 being secured to the support by means of a fastening element 83, which extends through the sleeve and engages the adjacent end of the support. The lower end of the inner member of the support is bent laterally to provide a supporting foot 84, which rests upon the lower wall of the intermediate or egg compartment 3 and is secured thereto by means 30 of fastening elements 85. The outer slidable member of the support is adapted to be held in adjustable position by means of a set screw 86 that is adjustable through the outer member and through the inner member, as shown in Fig. 9 of the drawings. The extended terminal of the forward end of the rod 52 engages beneath a bowed spring 87 and extends over the bill of a hook 88, which hook depends from the upper wall of the 45 intermediate compartment 3. The spring 87 exerts a downward force on the adjacent end of the rod 52 and an upward force on the forward ends of the dampers, so as to cause the rod 52 to engage the lower wall of the 50 the opening in the flange 35, and spaced from the upper wall of the said opening. This is advantageous in that when the dampers are in closed position any further expansion of the thermostat will result in the 55 movement of the forward end of the rod 52 against the tension of the spring 87, which spring will give under the upward movement of the rod and thereby prevent injury being done to the rod 52. The hook 88 engages the 60 adjacent terminal of the rod 52 when the dampers are moved downwardly, and limits the downward movement of the dampers.

It is evident that various changes may be resorted to in the construction, form and arrangement of the several parts without de-

parting from the spirit and scope of the invention; hence I do not limit myself strictly to the structure herein described and claimed.

Having thus described my invention what I claim as new, is:

1. An incubator including a casing, having a pair of spaced heating compartments, and an intermediate egg compartment, a damper for each heat compartment for controlling the entrance of heat into the 75 egg compartment, and adjustable means connecting the dampers together, whereby one damper can be arranged to be closed before the other, and a thermostat operatively connected to said means. 80

2. In an incubator having an egg compartment therein and a heating compartment arranged above the egg compartment, a pair of dampers for controlling the flow of heat into the compartment, said dampers 85 being hingedly supported at their rear ends, a strip connecting the forward ends of the dampers, an operating rod engaging said strips, means engaging said rod for limiting the downward movement of said 90 dampers, and a thermostat arranged in said egg compartment and operatively connected to said operating rod. 95

3. In an incubator, a casing, a partition arranged in said casing and dividing the same into a heating compartment and an egg compartment, said partition having spaced openings arranged therein, a pair of dampers hingedly connected at their rear ends to said casing and arranged to close said openings, a plate pivotally secured adjacent its rear end to said partition, an operating rod carried by the forward end of said plate and connected to said dampers, and means for limiting the downward movement of said operating rod, a pair of thermostats arranged in said egg receiving compartment, an arcuate bar supported by said thermostats, and a pin carried by said arcuate member and pivotally secured to 105 said pivoted plate, as and for the purpose specified. 100

4. In an incubator including a casing, a partition arranged in the casing and forming an egg receiving compartment and a 115 heating compartment, said partition having a pair of spaced openings, a damper for each opening hingedly secured adjacent its rear end to said casing, and a strip connecting the forward ends of said dampers, 120 means for limiting the downward movement of said dampers, a plate pivotally supported adjacent its rear end, an operating rod carried by the forward end of said plate and connected to said strip, a pair of thermostats, positioned in said egg receiving compartments, an arcuate bar supported by said thermostats, a pin supported by said arcuate bar and pivotally secured to said pivoted plate intermediate the operating rod and 125 130

the pivot point of said plate, and a wedge interposed between said pin and said arcuate bar, said wedge being manually operated and adapted to vary the distance between the arcuate member and said pin, as and for the purpose specified.

5. In an incubator of the above character including a heating compartment, and an egg compartment, a damper for controlling communication between said compartments, a thermostat located within the egg compartment, a member disposed above the thermostat and arranged to swing in a vertical plane, a connection between the 10 vertically movable member and the damper, 15 a pin depending from the vertically mov-

able member, a horizontally slidable and vertically movable element disposed above the thermostat and having a channel therein for receiving the lower end of the pin, the 20 said element being adapted from the expansion of the thermostat to be moved upwardly and cause upward movement of the vertically movable member so as to effect closing of the damper.

25 In testimony whereof I affix my signature in presence of two witnesses.

RUDOLPH POKOY.
